EDGE SETTING MACHINE

Eugene J. Ray, Beverly, Mass., assignor to United Shoe Machinery Corporation, Flemington, N. J., a corporation of New Jersey

Application April 16, 1941, Serial No. 388,851

4 Claims. (Cl. 12—78)

This invention relates to finishing machines and is illustrated herein as embodied in an improved machine for setting the edges of soles of shoes.

In machines of the general type disclosed in United States Letters Patent No. 2,283,204, granted May 19, 1942, upon the application of William Hamann, there is provided a tool holder which is oscillated at a high speed about a horizontal axis and has a cylindrical recess which is inclined at slightly less than 90° to said axis and in which fits a cylindrical spindle of a carrier having clamped to it an edge setting tool. When the machine is idle, the carrier is moved to an outward or lowered position in the holder away from said horizontal axis by a thrust spring, operating against the inner end of the carrier spindle, until an upper wall of a groove formed in the side of the spindle engages a torsion-resisting leaf spring which is secured to the holder and has a flat end face shaped and arranged to engage a flat bottom of said groove. During the edge setting operation, the operator forces the edge of the sole of the shoe being operated upon upwardly against the tool as he feeds the shoe past the tool, causing the carrier to slide in the cylindrical recess of the holder toward said axis of oscillation against the action of the thrust spring.

In order to enable the operator to follow edge portions of the sole which are curved heightwise of the shoe, the carrier is permitted to turn to a slight degree in the recess of the holder about the axis of its spindle against the action of the leaf spring which, by reason of the engagement of its flat end face with the flat bottom of the groove formed in the side of the spindle, normally retains the carrier, and therefore the tool, in a neutral position in which the planes of the lengthwise elements, respectively, of the work-engaging face of the tool are arranged approximately parallel to the general plane of oscillation of said axis of the spindle, said spring also resisting turning movement of the carrier spindle about its axis away from said neutral position under pressure of the work.

It will be appreciated that the leaf spring should be stiff enough to retain the tool carrier in said neutral position when the machine is running but no work is presented thereto and also when the tool is operating upon a straight run of the edge of the sole. On the other hand, the leaf spring should be sufficiently yieldable to enable the carrier to be turned slightly in the holder about the axis of the carrier spindle

under pressure of the work against the tool so as to enable the operator readily to follow changes in the curvature of the sole edge heightwise of the shoe. It is impracticable, however, to provide a relatively yieldable leaf spring, such as above referred to, in machines now in use, since the carriers and the many interchangeable tools of such machines are not statically balanced with relation to the axis of the spindle, the arrangement now being such that when the machine is running with no work presented thereto, the tool turns or vibrates rapidly back and forth about the axis of the spindle of the tool carrier as the holder is oscillated about the horizontal axis.

Moreover, the center of pressure exerted by the edge of the sole against the work-engaging faces of the various tools is commonly located a considerable distance to one side of the axis of the spindle, the distance from said axis usually varying in accordance with the size and shape of the operative face of the tool. Accordingly, the unbalanced force exerted by the work against the tool will, during the edge setting operation, cause the tool holder constantly to vibrate or turn back and forth rapidly in the recess of the holder in which it is mounted against the action of the above-mentioned spring, which, in order to be effective, should be strong enough to reduce such vibrating movement of the tool carrier about its spindle axis in the holder to a minimum.

It will be appreciated that when the tool vibrates rapidly in the holder about the axis of the spindle, it does not set the sole edge to a cross-sectional outline complementary to the transverse sectional outline of the operating face of the tool but, instead, imparts to the edge of the sole a slightly different and indeterminate cross-sectional outline. Moreover, when the tool is swung continuously about the axis of the carrier spindle as above described, the beveled edge formed by the lip of the tool and, in some cases, beads formed along the sole edges by lengthwise extending grooves in the work-engaging face of the tool, are ragged or of nonuniform widths.

On the other hand, it has been found that when the machine operates upon thin edges of soles, and especially upon the marginally reduced edges of shank portions of women's shoes, the maximum pressure that can be safely exerted against the tool by the thin edge of the sole during the edge setting operation is not always sufficient to rotate the carrier spindle in the tool holder against the pressure of the stiff spring, with the

result that the tool does not turn readily about the axis of the spindle so as to enable the operator quickly and effectively to guide the edge of the shank portion of the sole as it does under pressure of relatively thick portions of the fore-parts of the sole edges, for example.

It will therefore be appreciated that it is desirable to overcome the constant vibration of the tool about the axis of the carrier spindle during the edge setting operation and that it is equally desirable to insure that the tool may be readily turned about said axis under light pressure of the work so that the sole edge portions which are curved heightwise of the shoe may be moved quickly and effectively past the tool with the lengthwise elements of the work-engaging face of the tool disposed approximately lengthwise of the adjacent edge of the sole.

In edge setting machines having high speed, short stroke tools, it is essential that the tool shall at all times be rigidly secured to its carrier, since even a small play such as exists between tools and tool carriers of edge setters now commonly used will rapidly become greater and greater, due to wear between these parts, and will ultimately result in the tool being rendered ineffective and will necessitate replacing the tool or its carrier or both.

It is an object of the present invention to provide an improved machine in which the above-mentioned difficulties have been overcome and by the use of which edges of soles of shoes may be quickly and effectively set with a minimum amount of effort on the part of the operator.

With the above considerations in view, the tool carrier and the tool of the illustrative machine, which are supported for movement by mechanism practically identical with that disclosed in said Patent No. 2,283,204, are, in accordance with a feature of this invention, statically balanced with relation to the axis of the spindle of the carrier. Moreover, in accordance with a further feature of the invention, the tools, which have work-engaging faces of different widths and are secured interchangeably to the carrier, are so located in the carrier that, regardless of the size of the tool, the central parts of their work-engaging faces, and therefore the centers of pressure of the work against said faces, lie approximately in the axis of the spindle of the carrier. With such a construction, it has been found that the carrier and the tool secured thereto do not have the above-mentioned tendency to vibrate about the axis of the carrier spindle, either when the machine is running and there is no sole being presented to the machine or when the sole is being operated upon by the machine. By statically balancing the tool and the carrier about the axis of the carrier spindle and causing the center of pressure of the work against the work-engaging face of the tool to lie approximately in the axis of the spindle, it has been found that a relatively weak leaf spring can be used to retain the tool in its neutral position in which lengthwise elements of the work-engaging face of the tool are parallel to the plane of oscillation of said axis of the carrier spindle. It will be appreciated that by providing a relatively yieldable leaf spring such as above referred to, the tool can be readily turned about the axis of the carrier spindle under pressure of the work so as to enable the operator quickly and effectively to feed past the tool portions of the sole edge which are sharply curved heightwise of the shoe. Moreover, it has been found that the improved machine is much

easier, from the viewpoint of strain on the operator, to operate than machines now in use and that the edge set by the machine is well defined and complementary to the widthwise outline of the work-engaging face of the tool.

The arrangement disclosed herein for clamping the tool securely to the carrier constitutes the subject matter of my co-pending application Serial No. 438,479, filed April 10, 1942 as a division of the present application.

The various features of the invention will be understood and appreciated from the following detailed description read in connection with the accompanying drawing, in which

15 Fig. 1 is a front view of portions of the operating head of the illustrative edge setting machine;

20 Fig. 2 is a side elevation, partly in section, of the portions of the machine shown in Fig. 1 in the process of setting the edge of a sole of a shoe;

25 Fig. 3 is a perspective view of the lower end of a tool carrier of the machine;

30 Fig. 4 is a perspective view of one of several edge setting tools which may be secured interchangeably to the carrier;

35 Fig. 5 is a side view of the lower end of the carrier and an edge setting tool which is secured to the carrier;

40 Figs. 5A, 5B and 5C are side views, respectively, of different edge setting tools, any one of which may be secured to the carrier in place of the tool shown in Fig. 5;

45 Fig. 6 is a front view of the carrier and the tool shown in Fig. 5; and

50 Fig. 7 is a front view of the tool shown in Fig. 5C.

The illustrative machine is described with reference to setting the edges 20 (Fig. 2) of soles 22 of shoes and comprises a holder 24 (Figs. 1 and 2) which is mounted for reciprocation, oscillation or vibration about an axis 26 and has one or more heads 28 each provided with a cylindrical recess 30. Slidably fitting in each of the recesses 30 is a cylindrical spindle or shank 32 of a carrier 34 which is mounted for bodily reciprocation or oscillation in a plane and to which is secured, through means which will be described later, an edge setting tool 36 having a work-engaging face 38. The machine is of the high speed, short stroke type and, except for certain improvements in the carrier, the tool, and means for interchangeably securing tools having work-engaging faces of different shapes and widths to the carrier, is identical with the machine disclosed in said application Serial No. 335,725, which may be referred to for a detailed description of the machine.

In setting the edges 20 of soles 22 of shoes, the operator forces the sole of the shoe upwardly, as shown in Fig. 2, with considerable pressure against the work-engaging face 38 of the tool 36 as he feeds the shoe past the tool. The work-engaging faces of the edge setting tools vary in width in accordance with the width of the sole edge to be operated upon and are also of varying cross-sectional shapes in accordance with the desired shape to be imparted to the edge of the sole. Each of the illustrative tools 36 has a work-engaging face comprising a lip face 40 (Fig. 4), bead forming grooves 42, a bed 44, and a stepped guard face 46. In order to facilitate feeding portions 48 (Fig. 2) of the sole edge 20, which are curved heightwise of the shoe, past the tool 36, and to insure against the sole edge being pre-

sented at such an angle to the tool that the tool mars the appearance of the sole edge, as will be explained later, the carrier 34 is mounted for turning movement about the axis 50 of its spindle 32. In setting portions 48 of the sole edge 20 which are curved heightwise of the shoe, the tool 36 is turned slightly about the axis 50 away from its neutral or central position in which lengthwise elements 52 (Fig. 4) of the work-engaging face 38 of the tool lie in planes parallel to the plane of oscillation of said axis 50 about the axis 26. Such turning movement of the tool 36 is effected by the combined pressing and turning action of the sole edge 20 against the work-engaging face 38 of the tool, the carrier spindle 32 turning in the recess 30 of the holder 24 against the action of a torsion-resisting leaf spring 54 (Figs. 1 and 2) one end of which is secured by a screw 56 to the holder and a flat end face 58 of the other end of which engages a flat bottom 60 (Fig. 2) of a slot 62 formed in one side of the spindle 32 of the carrier 34.

In order to facilitate the initial presentation of the sole edge 20 to the work-engaging face 38 of the tool 36 and to insure that the sole edge is forced with an approximately constant pressure against the tool, said tool, as above stated, is mounted for sliding movement lengthwise of said axis 50 (that is, toward and away from the axis 26 about which the holder 24 oscillates) against the action of a thrust spring 64 (Figs. 1 and 2). Sliding movement of the carrier 34 toward the axis 26 is effected by pressure of the work against the tool 36, the carrier 34, when no work is presented to the machine, being moved downwardly away from the axis 26 by the thrust spring 64 which is carried by the holder 24 and has secured to it a ball 66 fitting in a recess in the end of the carrier. In order to limit movement of the carrier 34 toward the axis of oscillation 26 of the holder, the carrier is provided with a flange 68 which, if the work exerts an unusually heavy pressure against the tool, is forced into engagement with a face 70 of the holder 24.

During the edge setting operation, the sole edge 20 usually bears against portions of the work-engaging face 38 of the tool which are located between the outer portion of the lip face 40 and the outer portion of the guard face 46. The grooves 42, which are parallel to the lengthwise elements 52 (Fig. 1) of the work-engaging face 38, are shaped and arranged to form beads 72 (Fig. 2) at the margins of the sole edge.

In machines now in common use, the resultant force exerted by the sole edge against the work-engaging face of the tool is applied at a point which is offset a considerable distance laterally from the axis of the carrier spindle, the amount of offset being greater, for example, in the case of a forepart tool having a work-engaging face of small width than in the case of a forepart tool having a work-engaging face of large width. It will thus be clear that when the sole edge is forced against the work-engaging face of each of such tools, the drag of the work against the tool causes the tool and the carrier to which it is secured to turn or vibrate rapidly about the carrier spindle axis against the action of the leaf spring. Moreover, in machines now in common use, the carriers and the various tools secured interchangeably to the carriers are not statically balanced about the axes of the respective carrier spindles and turn or vibrate rapidly about said axes due to their centers of mass being offset from the axes, the degree and

rapidity of vibration varying in accordance with the particular tools secured to the carriers.

When the machine is running idle (no work at such time being presented to the machine), and 5 also when the machine is operating upon straight runs of sole edges 20, it is desirable that the lengthwise elements 52 (Fig. 4) of the work-engaging face 38 of the tool 36 shall lie in planes which are parallel to the plane of oscillation of 10 the axis 50 of the spindle 32 of the carrier 34. It will be appreciated that when a tool or its carrier or both are unbalanced with reference to the carrier spindle axis 50, as in the case of machines now in use, such tools will constantly 15 turn or vibrate about said axis, both when the machine is running idle and when it is operating upon a shoe. Such a condition, for reasons above stated, is undesirable and may be remedied to a considerable extent by providing an excessively stiff torsion-resisting leaf spring corresponding to the leaf spring 54, which, as will appear later, is relatively weak.

On the other hand, it is highly important that the tool shall turn readily about the axis 25 50 of the carrier spindle 32 when slight turning pressure is exerted against the tool by the sole edge 20, it having been found that when a heavy turning pressure is exerted by the work against the tool the edge of the sole of the shoe sometimes slips off the tool, with the result that the outer ends of the lip and guard faces 40, 46, respectively, of the tool chew a portion of the sole edge. Accordingly, if the leaf spring 54 is 30 too stiff, the portions 48 of the sole edges which are curved sharply heightwise of the shoe have to be fed past the tool extremely carefully and therefore slowly, it having been found that, even under such conditions, unless the operator moves the shoe in a curved path approximating the 35 curvature of that portion of the sole being trimmed, the edge of the sole is likely to have a sufficient component of movement widthwise of the tool to cause the sole edge to be damaged, as above described. It will be noted that if the 40 edge of the sole is relatively thin, sufficient force cannot always be exerted against the tool by the sole edge to turn the same about the carrier spindle axis when the torsion-resisting leaf spring is stiff.

50 With the foregoing considerations in view, the illustrative machine is provided with means, which will appear later, for causing the centers of the work-engaging faces 38 of the tools 36, regardless of the width of said faces, to be positioned in approximate alignment with the axis 50 of the carrier spindle 32, thereby insuring that the frictional drag by the work against the work-engaging face of the tool shall not continuously 55 vibrate the tool about the axis of the carrier spindle, as above described, during the operation 60 of the machine.

In high speed, short stroke edge setting machines it is highly important that there shall not be any movement between the carrier 34 and the 65 tool 36, it having been found that if there is any play whatsoever between the carrier and the tool, there will be a rapidly increased wear between these parts, with the result that the tool or the carrier or both have to be discarded.

70 With the foregoing in view, the carrier 34 is provided with a large, flat face or abutment portion 74 (Fig. 3) disposed at right angles to the axis 50 of the carrier spindle 32, and an overhanging or undercut shoulder 76 (Figs. 3 and 6) 75 which forms a V-shaped notch 78 with an ad-

adjacent portion of the surface 74. Each of the tools 36, irrespective of the width of its work-engaging face 38, is provided with a dovetail portion 80 of the same size (approximately one-half inch wide, as indicated by reference numeral 82, Fig. 5A) having a flat abutment face 84 and undercut wedge faces 86 which terminate at the ends of said abutment face. It has been found that if the flat abutment face 84 of the tool can be clamped with considerable wedging pressure against the flat abutment face 74 (Fig. 3) of the carrier 34 and can be effectively held against movement on said face, there will not be any movement between the tool and the carrier during the operation of the machine. Accordingly, there is provided a clamp comprising a plate 88 one end of which fits in an elongated slot 90 of the carrier and the other end of which is constructed and arranged to engage one of the undercut wedge faces of the dovetail portion of the tool and to force the other wedge face of said dovetail portion against the undercut shoulder 76 of the carrier 34. Upon rotation of a screw 92 which is threaded into the carrier 34 and extends through a recess 94 (Fig. 6) in the plate 88, the head of the screw causes the plate to swing in a clockwise direction, as viewed in Fig. 1, about its upper end, with the result that the flat abutment face 84 of the tool is forced by a wedging action against the flat abutment face 74 of the carrier, the tool being secured against movement in the carrier by the shoulder 76 of the carrier and the lower end of the plate 88. The tool carrier 34 and its associated clamp may thus be described as forming between them a dovetail recess 96 (Fig. 3) having a flat bottom 74 against which the flat abutment face 84 of the tool 36 is forced, as above described. This recess constitutes a guideway extending transversely of the path of movement of the carrier and parallel to the direction in which the width of the tool is measured. It will be noted that the wedge faces 86 of the tool 36 are shaped and arranged to extend out of and beyond the dovetail recess 96.

In order to eliminate, or at least to reduce to a minimum, the above-mentioned tendency of the carrier 34 and the tool 36 continuously to turn or to vibrate about the axis 50 of the carrier spindle 32, the illustrative machine, in addition to positioning the central part of the work-engaging face 38 of the tool in the axis of the carrier spindle, has its carrier and tool statically balanced with reference to said axis.

As above stated, the dovetail portions 80 of the various tools are of the same size, the width of said portion being approximately one-half an inch and equal to the distance between the front face 98 of the carrier 34 and a stop pin 100 (Figs. 1, 3 and 6) which is secured to the carrier and projects from the abutment face 74 thereof. The axis 50, which may be described as intersecting the carrier 34, is positioned equidistant from the front face of the carrier and the stop pin 100. In edge setting tools 36 having work-engaging faces 38 which are narrower than one-half an inch, for example, the front and rear faces 102, 104 (Figs. 4, 5 and 5A) of the tool 36 converge toward the work-engaging face 38 of the same. In tools having work-engaging faces 38 wider than one-half an inch, the tool has a pair of forwardly and rearwardly extending flanges 106, 108, respectively (Figs. 5B and 5C). As above stated, the distribution of weight of each of the tools 36 is such that when the tool is

positioned in the carrier 34 with the rear face 110 (Figs. 5A, 5B and 5C) of its dovetail portion 80 in engagement with the stop pin 100, the tool is statically balanced about the carrier spindle axis 50. The carrier 34, which comprises the clamp by which the tool 36 is secured to the carrier, is also statically balanced about the carrier spindle axis 50. It will therefore be clear that when the machine is running idle, there will be little, if any, tendency for the tool 36 to turn about the carrier spindle axis 50. Moreover, since the centers of the work-engaging faces 38 of the various tools are in alignment with the carrier spindle axis 50, there will be little tendency for the tool to vibrate about said axis during the operation of the machine. With such a construction, it is possible to use the torsion-resisting leaf spring 54, which is relatively weak and is therefore adapted yieldingly to rotate readily under pressure of the work, thereby enabling the operator quickly and effectively to move portions 48 of the sole edge 20, which are curved sharply heightwise of the shoe, past the tool without danger of moving the sole edge across the path of oscillation of the tool and therefore damaging the sole edge.

Having described my invention, what I claim as new and desire to secure by Letters Patent of the United States is:

1. An edge setting machine comprising a carrier mounted for bodily oscillation about an axis and also for turning movement about an axis which is disposed at a substantial angle to the first-named axis, said carrier having a guideway for receiving interchangeably any one of a plurality of edge setting tools having work-engaging faces of different width, said guideway extending transversely of the path of oscillation of the carrier and parallel to the direction in which the width of the tool is measured, a stop engageable with each of said tools to determine the position of the tool in the guideway, each of said tools irrespective of the width of its work-engaging face being constructed and arranged to have the central portion of its work-engaging face in approximate alignment with the second-named axis when the tool engages said stop, and means for securing the positioned tool in the guideway.

2. An edge setting machine comprising a carrier which is mounted for bodily vibratory movement and also for turning movement about an axis, said carrier having a guideway for receiving interchangeably any one of a plurality of edge setting tools having work-engaging faces of different character, said guideway extending transversely of the path of vibration of the carrier and parallel to the direction in which the width of the tool is measured, an edge setting tool which is one of said plurality in said guideway, a stop engageable with said tool to determine the position of the tool along the guideway, each of said tools irrespective of the character of its work-engaging face being constructed and arranged to be statically balanced with reference to said axis when the tool engages said stop, and a clamp for securing the positioned tool in the guideway.

3. An edge setting machine comprising an edge setting tool, a carrier for said edge setting tool, driving means for reciprocating the carrier and the tool approximately in a plane, a connection between said carrier and said driving means constructed and arranged to permit turning of the tool about an axis lying approximately in said plane, resilient means for yieldingly holding said tool in a predetermined neutral position of rota-

tion about said axis, said neutral position being such as to cause the lengthwise elements of the work-engaging face of the tool to be approximately parallel to said plane, said carrier having a guideway in which said edge setting tool may be moved in a direction normal to said plane, a stop for limiting the movement of the edge setting tool in the guideway, said edge setting tool being one of a plurality of edge setting tools having different characteristics, each tool of said plurality being designed to engage said stop in a desired relation to the axis about which the tool carrier may turn, and a clamp for securing the tool in stopped position in said guideway.

4. An edge setting machine comprising an edge setting tool, a carrier for said tool, driving means

for vibrating the carrier to give the tool an operative movement, said carrier having a guideway along which said tool may be positioned, said guideway extending transversely to the path of vibration of the tool and parallel to the direction in which the width of the working face of the tool is measured, said tool being one of a plurality of tools having different characteristics and adapted to be interchangeably received in said guideway, a stop for determining the position of the tool in the guideway, each tool of the plurality being designed to engage said stop in a desired position with respect to the characteristics of that tool, and a clamp for securing the tool in said stopped position in said guideway.

EUGENE J. RAY.
